(57) CLAIM

The ornamental design for a body sculpting garment as shown and described.

DESCRIPTION

FIG. 1 is a front view of a body sculpting garment according to a first embodiment of the design;

FIG. 2 is a rear view thereof;

FIG. 3 is a right side view thereof;

FIG. 4 is a front view of a body sculpting garment according to a second embodiment of the design;

FIG. 5 is a rear view thereof; and,

FIG. 6 is a right side view thereof.

The broken lines along the surfaces of the body sculpting garment depict stitching, which forms no part of the claimed design. The broken line outline of the humanoid figure assists in illustrating how the body sculpting garment may appear when in a position of use but forms no part of the claimed design.

1 Claim, 6 Drawing Sheets
